UNITED STATES PATENT OFFICE.

JAMES M. LEAVER, OF LONG BEACH, CALIFORNIA.

DRY-KILN FOR LUMBER, &c.

1,135,301.

Specification of Letters Patent. Patented Apr. 13, 1915.

Application filed April 4, 1914. Serial No. 829,593.

To all whom it may concern:

Be it known that I, JAMES M. LEAVER, a citizen of the United States, residing at Long Beach, in the county of Los Angeles and State of California, have invented a new and useful Dry-Kiln for Lumber, &c., of which the following is a specification.

The invention relates to improvements in kilns for drying lumber and other material. 10 The object of the present invention is to improve the construction of dry kilns, more especially that shown and described in an application filed by me on or about May 24, 1912, Serial No. 699,578, wherein certain of 15 the ducts or passages are equipped with vertical heating pipes to insure the greatest possible velocity of internal circulation, and to arrange such ducts in such a manner as to draw their entire air supply from the 20 interior of the kiln room or drying chamber practically from the floor level or other desired point to suit the conditions of a kiln, and to eliminate the separate chamber for 25 mixing the heated moist air with the cold or outside air before the latter is introduced 30 into the drying chamber by causing the cold or outside air introduced into the drying chamber or kiln room to commingle with the hot moist air at the top of such chamber or room before reaching the lumber or other material to be dried.

A further object of the invention is to provide a dry kiln of this character, adapted to maintain great internal circulation without depending for the same upon the escape of the hot moist air to the chimney or stack, and at the same time enable such draft to be utilized for carrying away the moisture and controlling and maintaining the proper 40 amount of moisture within the kiln and for also automatically controlling the inlet of cold or outside air to the drying chamber or kiln room, thereby permitting a gradual reduction of moisture and an increase of heat 45 as the drying process progresses.

Furthermore, the invention has for its object to provide a dry kiln having means for maintaining perfect control of the temperature and moisture conditions at all 50 times, and in which the internal circulation may be maintained without permitting any greater amount of moist heated air to escape than is compatible with the temperature and moisture desired, thereby producing ideal 55 conditions for the proper drying of all kinds of lumber.

Another object of the invention is to provide a dry kiln having its ducts or passages arranged for producing an internal circulation transversely of the drying chamber or kiln room and in which the intensity of the circulation will not be interrupted or interfered with by the control of the draft to the chimney or stack, and which will also admit of graduation in temperature from one end 60 of the kiln room to the other for progressive drying, or the maintenance of a uniform temperature from one end of the chamber or room to the other to dry all the lumber, so that the entire contents of the kiln room or 65 chamber may be discharged at one time when the drying has proceeded as far as desired.

With these and other objects in view, the invention consists in the construction and 70 novel combination of parts hereinafter fully described, illustrated in the accompanying drawings, and pointed out in the claims hereto appended; it being understood that various changes in the form, proportion, 75 size and minor details of construction, within the scope of the claims, may be resorted to without departing from the spirit or sacrificing any of the advantages of the invention.

In the drawings: Figure 1 is a transverse sectional view of a portion of a dry kiln, constructed in accordance with this invention, the section being taken in the plane of one of the recirculating ducts or passages. 80 Fig. 2 is a similar view, the section being taken in the plane of one of the cold air ducts or passages. Fig. 3 is a horizontal sectional view of a portion of the kiln. Fig. 4 is a vertical longitudinal sectional view, 85 taken substantially on the line 4—4 of Fig. 1. Fig. 5 is a detail horizontal sectional view on the line 5—5 of Fig. 1. Fig. 6 is a detail transverse sectional view on the line 6—6 of Fig. 3. Fig. 7 is a similar view on 90 the line 7—7 of Fig. 3. Fig. 8 is a detail sectional view, illustrating the arrangement of the gutters of the roofs. Fig. 9 is a plan view of a portion of the kiln, illustrating another form of the invention in which the 95 ducts or passages are staggered.

Like numerals of reference designate corresponding parts in all the figures of the drawings.

In the accompanying drawings in which 110 is illustrated the preferred embodiment of the invention, the dry kiln, which may be

constructed in a series or consist of a single drying chamber or kiln room 1, comprises in its construction side walls 2 and 3, designed to be constructed of any suitable material, and in the form of invention illustrated in Figs. 1 to 7 inclusive, the kiln is provided with an inclined roof 4 and a horizontal floor or bottom 5. The roof extends upwardly from the wall 2 to the wall 3, and in a series of kilns a suitable gutter 6 will be provided at the adjacent lower portions of the two oppositely inclined roofs, as clearly illustrated in Fig. 8 of the drawings. The gutter 6, which is preferably constructed of galvanized sheet iron, consists of oppositely inclined bottom portions 6^a, vertical side walls 6^b and inclined lateral extensions 6^c. The inclined bottom portions 6^a extend downwardly and inwardly to the median line of the gutter and the inclined laterally extending side portions 6^c are secured to the adjacent portions of the roofs of the adjoining kiln rooms. The outer laterally extending portions 6^c are preferably overlapped by the roof paper or other roofing material and the vertical side portions 6^b of the gutter extend downwardly from the lower edges of the roofs 4 to the oppositely inclined bottom portions 6^a. The inclined bottom portions 6^a and the vertical side portions 6^b are preferably supported by boards or pieces 4^a and 4^b, arranged at an inclination to fit the inclined bottom portions of the gutter and vertically to fit the sides of the same.

The side wall 2 is equipped with vertical cold air ducts or passages 7 and vertical recirculating ducts or passages 8, extending from the top to the bottom of the drying chamber or kiln room and preferably arranged contiguous to one another so that the cold or outside air entering the drying chamber or kiln room at the upper portion thereof through upper openings 9 of the cold air duct or passage will commingle with the heated moist air discharged from the upper ends of the recirculating ducts or passages 8 through upper openings 10. These vertical ducts or passages 7 and 8 may be alternately arranged, as illustrated in Fig. 3 of the drawings, but they can be arranged in any other preferred manner. The ducts or passages 7 and 8 are separated by studding 11, the spaces between the studding being covered at the interior of the kiln to form the passages 7 and 8, but the latter may be constructed in any other preferred manner.

Each cold air duct 7 communicates at its lower end with an inlet opening 12 in the bottom of the floor 5, a cold air intake box connecting the lower end of the duct or passage 7 with the opening 12. The cold air intake box is composed of spaced approximately triangular blocks 13 and an inclined

wall 14, fitted against and suitably secured to the inclined edges of the triangular blocks 13. The blocks, which have inner inclined edges, form the end walls of the intake box, and the inclined wall 14 extends upwardly and outwardly from the floor 5 at the inner side of the opening 12 to a horizontal bar 15, suitably secured to the studding and fitted against the upper ends of the blocks 13, which are slightly truncated, as shown. The intake box forms a short passage or entrance connecting the vertical duct or passage 7 with the exterior and adapted to prevent the cold or atmospheric air from passing directly into the drying chamber or kiln room. The inlet or passage of cold air through the duct 7 is automatically controlled by the means hereinafter described, and the cold air ascending the ducts or passages 7 is slightly heated and its temperature on leaving the upper ends of the cold air ducts is slightly higher than that of the outside atmosphere. The upper edges of the inner inclined side walls of the cold air intake boxes are preferably fitted against the lower edges of the horizontal bars 15.

The recirculating ducts 8 are equipped with vertical steam pipes 16 preferably arranged in the form of radiators and connected at the bottom of the drying chamber with longitudinal feed and return pipes 17 and 18, the connecting pipes being equipped with suitable valves 19 for controlling the passage of the steam to the vertical heating pipes. Owing to the vertical heating pipes being arranged in vertical sections and each section being controlled by separate inlet and outlet steam valves, any graduation in temperature from one end of the drying chamber to the other can be maintained by shutting off certain sections, thus progressive drying may be had, or by using all of the sections of piping a uniform temperature from one end of the room to the other may be maintained, thereby simultaneously drying all of the lumber in the kiln, so that the entire contents of the drying chamber may be discharged at one time when the drying has proceeded as far as desired. The lower ends of the vertical recirculating ducts or passages 8 communicate with the drying chamber or kiln room at the bottom thereof through openings 20, and the longitudinal feed and return pipes 17 and 18 are arranged beneath inclined shields or partitions 21, extending upwardly and outwardly to the horizontal bars 15 and fitting against the same at a point above the inclined walls 14 of the cold air intake boxes. The inclined guards or partitions 21 have their lower edges spaced from the floor or bottom of the drying chamber to permit free passage of the heated moist air to the lower ends of the recirculating ducts or passages. The inclined shields or partitions 21 are secured to

inclined bars or cleats 22, arranged at and secured to the side faces of transverse braces 23 and supported at their lower ends by short vertical bars or pieces 24. The braces 23, which are horizontally disposed, extend from the side walls of the kiln to the supporting means of rails 25, and the outer ends of the said braces 23 are supported upon truncated triangular blocks 26, having horizontal upper and lower edges and presenting inclined inner edges, which are arranged in the same inclined planes as the inclined inner edges of the triangular blocks 13. The inner inclined walls of the cold air intake boxes 15 are supported at the braces 23 by strips or cleats 27, the truncated blocks 26 and the adjacent supported portions of the braces 23 constituting the end walls of the adjacent intake boxes. The horizontal bars 15 and the inclined guards or partitions extend longitudinally of the drying chamber or kiln room in the spaces between the braces 23. The rails 25, which may be supported in any suitable manner, are mounted upon stringers 28, which are supported by vertical posts 29, extending above the plane of the lower openings of the recirculating passages or ducts, so that the lumber piled upon a car 30 is located a considerable distance above the plane where the air from the drying chamber or kiln room enters the recirculating ducts or passages. The extending of the vertical steam pipes some distance below the level of the load of lumber to be dried tends to a greater efficiency of internal circulation, for, in order to maintain a very great internal circulation while not allowing more heated air to escape from the kiln than is compatible with the temperature and moisture desired to be maintained in the drying chamber or kiln room is to produce an ideal condition for drying, admitting as it does of a gradual reduction of moisture and an increase of heat as the drying process progresses. Given an equal pipe area of vertically arranged piping as compared with a horizontal arrangement of the heating pipes, the volume of air passing through the vertical recirculating ducts or passages is radically increased and especially so when the upward currents of air are confined in ducts, which act as chimneys. Thus a very strong internal circulation is maintained and at the outlet of the recirculating or heating ducts, the recirculated hot moist air strikes the currents of the outside air, which ascend the adjoining vertical ducts or passages 7 and a mixture of the two currents is effected during the passage of the same across the drying chamber in the space between the ceiling 31 and the load of lumber to be dried. The ceiling 31 slopes in the same direction as and is in parallelism with the roof, and owing to the sloping of the ceiling toward the opposite side of the room the currents of air following the line of least resistance travel transversely across the drying chamber or kiln room from one side of the same to the other. The tendency of the mixed currents of air is to descend adjacent to the side wall 3, and they pass through the courses of lumber toward the recirculating ducts or passages and also toward outlet ducts or passages 32, which are provided at intervals at the side wall 3 of the kiln. The outlet ducts or passages, which are vertical, extend from the bottom of the drying chamber to and are connected with a longitudinal suction chamber 33, located at the top of the drying chamber above an inclined ceiling section or partition 34, which connects the upper end of the inclined ceiling 31 with the side wall 3 of the kiln. The inclined ceiling terminates short of the side wall 3, and the inclined partition 34 extends downwardly from the ceiling to the said side wall 3. The longitudinally disposed inclined partition 34 besides dividing off the space within the kiln to form the longitudinal suction chamber also assists in changing the direction of the transverse currents of air to cause the same to travel downwardly at the side wall 3 of the drying chamber. The outlet ducts 32 are arranged at intervals and the spaces between the outlet ducts are uncovered and form passages 35, which assist the downward movement of the mixed currents of air in the circulation of the same through the drying chamber. The suction chambers 33 of the adjacent drying chambers or kiln rooms communicate at intervals with suitable chimneys or stacks 36 of sufficient number and capacity to produce the desired suction or draft through the longitudinal suction chamber 33 and the vertical outlet or suction ducts or passages 32. The outlet ducts or passages have openings 37 at their lower ends and the escape of the heated moist air through the outlet ducts to the chimney or stack is controlled by dampers 38, hinged at their upper edges 39 and arranged to close against inclined edges of triangular blocks 40, which are mounted at the lower ends of the outlet ducts at opposite sides of the opening 37. The hinged dampers, which are of a length when closed to extend to the bottom or floor of the drying chamber, are adapted to completely close the lower openings 37 of the outlet ducts. The dampers are connected by suitable flexible connections 41 with a longitudinal shaft 42, journaled in suitable bearings and preferably extending the entire length of the drying chamber or kiln room and equipped with a suitable operating handle 42^a, preferably arranged exteriorly of the kiln, as illustrated in Fig. 3 of the drawings. The longitudinal shaft 42 is adapted to be rotated by the crank handle 42^a to wind up the flexible connection or unwind it.

the same for adjusting the dampers, and a pawl and ratchet 43 or any other suitable device may be provided for securing the shaft and the dampers or valves in their adjustment. The bearings are mounted upon the horizontal track braces 23, which also support running boards 44. The cold air ducts or passages 7 are not equipped with dampers or valves, and they deliver only sufficient air to the drying chamber to fill the vacuum caused by the outgoing heated moist air. The action or operation of these cold air supply ducts 44 is automatically governed by the escape of the heated moist air. Naturally the walls of the cold air ducts being warm conduce to the raising of the temperature of the incoming outside or cold air during the passage of the same through the said ducts, so that when the outside or cold air meets the reheated moist air, it is higher in temperature than the outside air, this varying with the volume admitted and the temperature of the duct walls.

Preferably the vertical heating or recirculating ducts and the cold air ducts are located at one wall of the drying chamber, while at the opposite wall are arranged the outlet ducts and the open ducts, which assist the down draft. However, it may be advantageous to employ a staggered arrangement, as illustrated in Fig. 9 of the drawings, in which is illustrated a dry kiln provided at each of the walls 45 with cold air inlet ducts 46, recirculating or heating ducts 47, outlet ducts 48 and open ducts 49. The arrangement of these ducts at each side of the side walls do not correspond but are staggered, as shown, the cold air ducts of one side wall being located opposite the outlets of the other side wall, while the recirculating or heating pipes of one side wall are located opposite the open or down draft ducts of the other wall. This arrangement may be further varied, if desired, but it is preferable to arrange the cold air ducts adjoining the recirculating or heating ducts at each side wall, so that the currents from such ducts will mix or commingle in the manner heretofore explained before the cold air reaches the lumber to be dried.

When each side wall is equipped with the inlet, outlet, recirculating and open or down draft ducts, the roof will be oppositely inclined and provided at the center with a gutter similar in construction to that illustrated in Fig. 8 of the drawings. Any suitable means may be employed to increase the moisture in the usual manner as such means may be advantageously used where the stock has been partially air dried before being put in the kiln, or where the lumber does not contain sufficient moisture.

What is claimed is:—

65 1. A dry kiln including a drying cham-

ber, a chimney or stack, an outlet duct or passage communicating with the drying chamber and with the chimney or stack, an inlet duct or passage connecting the drying chamber with the outside atmosphere, and a recirculating duct or passage having heating means and extending from the lower to the upper portion of the drying chamber. 70

2. A dry kiln including a drying chamber, a chimney or stack, a damper controlled outlet duct or passage communicating with the drying chamber and with the chimney or stack, an air inlet passage or duct communicating with the outside atmosphere and with the drying chamber and automatically controlled by the escape of heated moist air through the outlet or passage, and a recirculating duct or passage having heating means and extending from the upper to the lower portion of the drying chamber 75 and communicating therewith. 80

3. A dry kiln including a drying chamber, a cold air duct or passage communicating with the outside atmosphere and with the drying chamber, and a recirculating 90 duct or passage having heating means for creating an upward circulation of air through it, said recirculating duct or passage communicating at its ends with the drying chamber and arranged to discharge 95 into the same adjoining the cold air inlet duct or passage, whereby a commingling or mixing of the outside air and the heated moist air is effected. 100

4. A dry kiln including a drying chamber, a recirculating duct or passage extending from the bottom to the top of the drying chamber and communicating at each end therewith and provided with heating means for creating an upward circulation of air 105 through it, and a cold air duct or passage communicating with the outside atmosphere and arranged to discharge into the drying chamber at a point adjacent to the upper end of the recirculating duct or passage to 110 effect a mixture or commingling of outside air and the reheated air before the outside air impinges against the material to be dried. 115

5. A dry kiln including a drying chamber, a vertical cold air duct or passage extending from the top to the bottom of the drying chamber and communicating at its lower ends with the outside atmosphere and at its upper end with the interior of the 120 drying chamber, and a vertical recirculating duct or passage also extending from the bottom to the top of the drying chamber and communicating at each end with the same, said recirculating duct or passage being provided with heating means for causing an upward circulation of air through it. 125

6. A dry kiln including a drying chamber, a vertical cold air duct or passage extending from the bottom to the top of the 130

1. A dry kiln including a drying chamber and communicating at its lower end with the outside atmosphere and having an opening at its upper end to discharge into the drying chamber, and a vertical recirculating duct or passage adjoining the cold air duct or passage and extending from the bottom to the top of the drying chamber and communicating at its lower end with the drying chamber at the 16 floor level, said recirculating duct or passage being provided at its upper end with an opening located adjacent to the opening at the upper end of the cold air duct or passage, and heating means located within 20 the recirculating duct or passage for causing an upward circulation of air through the said duct or passage.

2. A dry kiln including a drying chamber having a floor provided with an opening, a vertical cold air duct or passage extending from the bottom to the top of the drying chamber and discharging at its upper end into the same, and a cold air intake box mounted upon the floor and connecting the lower end of the said duct or 25 passage with the bottom opening.

3. A dry kiln including a drying chamber provided at its bottom with an opening, a vertical cold air duct or passage extending 30 from the bottom to the top of the drying chamber and discharging at its upper end into the same, and a cold air intake box connecting the lower end of the said duct or 35 passage with the bottom opening and comprising approximately triangular blocks located at opposite sides of the opening, and an inner inclined wall supported by the said blocks.

4. A dry kiln including a drying chamber, a plurality of vertical recirculating ducts or passages extending from the bottom to the top of the drying chamber and communicating at their upper and lower ends with the said chamber, vertical heating 40 pipes located within the recirculating ducts or passages, horizontal feed and return pipes arranged at the bottom of the drying chamber and connected with the vertical heating pipes, and inclined guards located 45 above the feed and return pipes and spaced from the bottom of the drying chamber to permit the air from the said drying chamber to pass into the lower ends of the recirculating ducts or passages.

5. A dry kiln including a drying chamber, vertical cold air ducts or passages extending from the bottom to the top of the drying chamber and discharging at their upper ends into the same, air intake boxes 55 arranged at the bottom of the drying chamber and connecting the lower ends of the cold air ducts or passages with the outside atmosphere, vertical recirculating ducts or 60 passages extending from the bottom to the top of the drying chamber and communicating at their lower ends directly with the said chamber, vertical heating pipes arranged within the recirculating ducts or passages, horizontal feed and return pipes connecting the vertical pipes and arranged exteriorly of the intake boxes, and guards extending from the ducts or passages and located above the feed and return pipes and spaced from the bottom of the drying chamber to permit the air therefrom to enter the recirculating ducts or passages.

6. A dry kiln including a drying chamber, vertical cold air ducts or passages extending from the bottom to the top of the drying chamber and discharging from their upper ends directly into the said chamber, cold air intake boxes having inner inclined walls and connecting the lower ends of the said ducts or passages with the outside atmosphere, vertical recirculating ducts or passages extending from the bottom to the top of the drying chamber and communicating directly with the interior thereof, vertical heating pipes arranged within the recirculating ducts or passages, horizontal feed and return pipes arranged at the bottom of the drying chamber and connected with the vertical heating pipes, and inclined guards arranged above the feed and return pipes at an angle to the inclined walls of the intake 70 boxes and spaced from the bottom of the drying chamber to permit the air therefrom to enter the lower ends of the intake ducts or passages.

7. A dry kiln including a drying chamber, vertical cold air ducts or passages extending from the bottom to the top of the drying chamber and discharging from their upper ends directly into the said chamber, cold air intake boxes having inner inclined walls and connecting the lower ends of the said ducts or passages with the outside atmosphere, vertical recirculating ducts or passages extending from the bottom to the top of the drying chamber and communicating directly with the interior thereof, vertical heating pipes arranged within the recirculating ducts or passages, horizontal feed and return pipes arranged at the bottom of the drying chamber and connected with the vertical heating pipes, and inclined guards arranged above the feed and return pipes at an angle to the inclined walls of the intake 80 boxes and spaced from the bottom of the drying chamber to permit the air therefrom to enter the lower ends of the intake ducts or passages.

8. A dry kiln including a drying chamber, a chimney or stack, a longitudinal suction chamber located at and extending along the upper portion of the drying chamber and connected with the chimney or stack, an outlet duct or passage extending from the suction chamber to the bottom of the drying chamber and communicating directly at its lower end with the said drying chamber, and a damper for controlling the escape of moist heated air through the outlet duct or passage.

9. A dry kiln including a drying chamber, a chimney or stack, an outlet duct or passage connected with the chimney or stack and extending to the bottom of the drying chamber and provided thereat with an opening communicating directly with the said drying chamber, approximately triangular blocks located at opposite sides of the said opening and presenting inner inclined edges, a hinged damper or valve arranged to close against the inclined edges of the blocks, and means for operating the valve.

10. A dry kiln including a drying chamber, a chimney or stack, a longitudinal suction chamber located at and extending along the upper portion of the drying chamber and connected with the chimney or stack, a plurality of outlet ducts or passages located at spaced points along the drying 125

- chamber extending from the suction chamber to the bottom of the drying chamber and provided at their lower ends with openings communicating directly with the said drying chamber, dampers or valves for controlling the escape of moist heated air through the outlet ducts or passages, and operating means connected with the dampers or valves for adjusting the same.
- 10 15. A dry kiln including a drying chamber, a cold air duct or passage extending from the bottom to the top of the drying chamber and communicating at its lower end with the outside atmosphere and at its upper end with the drying chamber, a recirculating duct or passage extending from the bottom to the top of the drying chamber and communicating at its ends directly with the said chamber, heating means located within the recirculating duct or passage for creating an upward circulation of air therein, an outlet duct or passage extending from the bottom of the drying chamber and communicating therewith directly with the interior of the said drying chamber, the cold air duct or passage and the recirculating duct or passage being located at one side of the drying chamber and the outlet duct or passage being located at the opposite side of the said chamber, and means for controlling the escape of moist heated air through the outlet duct or passage.
- 15 20 25 30 35 40 45 50 55 60 65 70 75 80 85 90 95 100
16. A dry kiln including a drying chamber provided with a plurality of spaced vertical outlet ducts or passages communicating at their lower ends with the drying chamber, open down draft ducts or passages located at the spaces between the outlet ducts or passages, a recirculating duct or passage located opposite the said ducts or passages and extending from the bottom to the top of the drying chamber and communicating at its ends with the said chamber, said recirculating duct or passage being provided with heating means for creating an upward circulation of air through it.
17. A dry kiln including a drying chamber having an inclined ceiling, a recirculating duct or passage extending from the bottom to the top of the drying chamber and communicating directly with the same and having its upper end located at the lower edge of the inclined ceiling, an outlet duct

or passage located opposite the recirculating duct or passage and extending from the bottom of the drying chamber and communicating therewith directly with the said chamber, and open down draft ducts or passages arranged adjacent to the outlet duct or passage.

18. A dry kiln including a drying chamber having an inclined ceiling terminating short of one side wall of the drying chamber, a suction chamber located at the upper portion of such side wall and having an inclined wall or partition extending from the ceiling to the said side wall, outlet ducts or passages extending from the bottom of the drying chamber to the suction chamber and arranged at spaced points, and open down draft ducts or passages located between the outlet ducts or passages and extending downwardly from the said inclined wall or partition.

19. A dry kiln including a drying chamber, vertical cold air ducts or passages extending from the bottom to the top of the drying chamber and communicating at their upper ends directly with the said chamber and at their lower ends with the outside atmosphere, vertical recirculating ducts or passages extending from the bottom to the top of the drying chamber and communicating at their ends directly with the said chamber, spaced vertical outlet ducts or passages extending from the bottom of the drying chamber and communicating at their lower ends directly with the said chamber, vertical down draft ducts or passages located at the spaces between the outlet ducts or passages, said down draft and outlet ducts or passages being located at one of the side walls of the drying chamber and the other ducts or passages being located at the opposite side wall, a longitudinal suction chamber communicating with the upper ends of the outlet ducts or passages, and a chimney or stack connected with the suction chamber.

In testimony, that I claim the foregoing as my own, I have hereto affixed my signature in the presence of two witnesses.

JAMES M. LEAVER.
